TIMING DEVICE FOR CONVEYERS

Norman W. Lyon, Springfield, Mass., assignor to
 Package Machinery Company, Springfield,
 Mass., a corporation of Massachusetts

Application October 12, 1940, Serial No. 360,896

7 Claims. (Cl. 198—22)

This invention relates to an improved timing mechanism for conveyers. In particular, it relates to such a mechanism for use with conveyers in which a stream of similar articles is carried along by frictional engagement between the articles and the conveyer to a machine or other device for handling separately either single articles or a number of the articles in groups. One example of such a machine and associated conveyer is the bottle hooding machine which forms the subject matter of my copending application for "Bottle hooding machine," Serial No. 267,459, filed April 12, 1939. The subject matter of the present invention represents an improvement over the timing mechanism disclosed in said aforementioned case and, for purposes of illustration only, is shown in conjunction with the conveying system of said earlier case. The applicability of the present device to other machines and mechanisms will be readily apparent to those skilled in the art once its principles of operation are understood.

One purpose of the present invention is to provide an improved timing device for arresting the forward motion of the leading one of a series of containers being carried by a conveyer, and then releasing said container so that it may be carried forward by the conveyer in timed relation to the receiving member of the handling machine. Another purpose is to provide a timing device which may be readily operated at high speeds in conjunction with high speed container handling machines. An additional purpose is to provide a timing device which can be used equally well with containers of different diameters without adjustment of the timing device itself. A further purpose is to provide a timing device in which the forward motion of the leading container is arrested by contact with a gate member which is released, in order to permit the container to proceed, by a periodically operated swinging latch, the latch being effective to release the gate member only when a container is in abutting relation to the gate member, the latch member itself in no way contacting the container, thereby preventing danger of breakage in cases where fragile containers are used. An additional purpose is to provide a timing device in which a container is arrested by a gate member which, when unlocked, is moved to permit passage of the container by means of the container itself as differentiated from devices in which the container is positively moved by the gate member, thus further minimizing the danger of breakage due to jamming of containers. The foregoing and other purposes will be

clear from the following disclosure of the preferred way to practice the invention as set forth in the specification and claims.

Referring to the drawings:

- 5 Fig. 1 is a top plan view showing generally the improved timing mechanism arranged for operation with the conveyer of the bottle hooding apparatus referred to above, a portion only of the bottle hooding machine being shown;
- 10 Fig. 2 is a fragmentary top plan view of the timing device on an enlarged scale and shows a container about to be stopped by the gate member;

- 15 Fig. 3 is an elevation of the parts of Fig. 2; and Figs. 4 to 6 are views showing the successive positions of the operating members of Fig. 2 as a container is first halted and then released so that it may proceed into the machine in proper timed relation.

- 20 Referring to Fig. 1, 10 is a central shaft extending upwardly from the base 11 of the bottle hooding machine of the type shown in the application referred to. Keyed to a sleeve 12 surrounding shaft 10 is a yoke 13 having a pair of arms 14. To each arm is pivoted as at 15 one end of a lever 16 having secured to its opposite end in any suitable manner a bottle elevating stool 16'. Intermediate its ends, each arm 14 is provided with a boss 17 having a hole therein through which extends a journal pin 18 to which is attached in any suitable manner a roller 19. These rollers 19 roll in a cam track 20 formed in cam member 21 non-rotatably mounted around the shaft 10. As is explained in the aforementioned pending application, yoke 13 is rotated at a constant speed around shaft 10 to carry the rollers around the cam track 20, and this cam track is shaped to cause the levers 16 to be pivoted upwardly and downwardly around pivots 15 to raise and lower the stools 16'.

- 45 Mounted symmetrically around shaft 10 and in line with the respective stools is a pair of bottle hooding heads not shown. These rotate in unison with the stools 16' and a bottle placed on a stool in the lowered position of the stool is raised up into the head and then lowered, the head acting during this motion of the bottle to place a hood over its mouth.

- 50 Bottles 24 and 24' are delivered to the machine in a continuous stream by the constantly operating conveyer arranged to carry the bottles along impositively on a series of plates 26, the bottles passing between a pair of guide rails 27 and 28. Attached to the outer rail 28 as by bolts 29, see Fig. 3, is my novel timing mechanism which in-

cludes a gate member in the form of a star wheel 30 protruding into the channel formed by the rails 27 and 28. This star wheel, as will be explained in detail, is arranged to halt the first bottle of the line carried in the conveyer until the proper time and then release that bottle so that it can then be carried forward into the machine where it will be engaged by a sweep 31. This sweep pushes the bottle along an arcuate guide member 32 and onto one of the stools 16 which at that time will be in proper position to receive the bottle. The bottle is then carried around by the stool and at the same time the hood placed on the mouth by elevating the bottle into the superposed head, the bottle being discharged from the stool by engagement with arcuate guide 34. Inasmuch as the details of the operation of the bottle hooding machine are the subject matter of the application above referred to it is believed that the foregoing description will suffice for a general understanding of the machine for the purposes of the present invention.

Referring to Figs. 2 to 6, the timing mechanism includes, in addition to the star wheel 30, a swinging arm 38 carrying a pawl 39 for holding the star wheel in the position of Fig. 4 against the pressure of a bottle 24 carried by the conveyer, and a synchronizing lever 40 and synchronizing latch 41 for engaging the pawl and periodically releasing the star wheel for rotation as in Fig. 6 to thereby permit the bottle of Fig. 4 to be carried into the machine. To this end, the star wheel 30 is fixed in any suitable manner to a stub shaft 45 mounted for rotation in the frame 46 of the mechanism. Also fixed to shaft 45 and between the wheel and the frame is a four-toothed ratchet wheel 47.

One end 48 of pawl 39, as indicated, cooperates with the teeth on the ratchet wheel, the pawl itself being pivotally carried between ears 49 formed by bifurcating one end of the swinging arm 38. Between the ears, arm 38 is provided with a pair of abutments 50 and 51 permitting pawl 39 to have a limited rocking motion. A spring 52 biases the pawl against abutment 51. At the end opposite to that carrying pawl 39, arm 38 is bifurcated and is loosely pivoted by ears 53 to a shaft 55 which is likewise loosely journaled in a boss 56 formed in the frame.

Synchronizing lever 40 is fixedly attached to shaft 55 between the ends 53 of arm 38 and has attached to one of its outwardly extending arms 58 one end of a spring 59 which is connected at its other end to the arm 38 to bias the pawl 39 against the ratchet.

The opposite end of synchronizing lever 40 carries the synchronizing latch 41, the latch being pivotally mounted between the ears 61 of the bifurcated end of the lever as at 62. Between the ears 61 and on one side of the pivot pin 62 is provided an adjustable abutment in the form of a bolt 63 threaded through the body of the lever and held in adjusted position by a lock nut 64. At the opposite side of pin 62 is a compression spring 65 which biases one end of the latch against the end of bolt 63. The opposite end of the latch is hook shaped as at 66 and is arranged to engage at certain times with a similar hook shaped end 67 on pawl 39. A lever 70 is fixedly attached to the lower end of shaft 55 and is given a periodic reciprocation by means of a link 71 connected to a swinging arm 73 pivoted to one end of the frame 76 of the machine and having at its opposite end a roller 75

77 bearing against a cam 78. This cam 78 is driven in timed relation to the bottle hooding mechanism and the motion imparted to lever 70 through the link 71 results in synchronizing lever 40 being reciprocated to and away from the guide rail 28 periodically from the position of Fig. 2 to that of Fig. 4.

With the bottle hooding machine in operation the timing device functions as follows. The star wheel is left by a passing bottle 24 in the position of Fig. 2. The spring 52 holds the pawl 39 rocked against the abutment 51 while the spring 59 pulls the swinging arm 38 in a clockwise direction so that the end of the pawl 39 rests against the ratchet wheel 47. At this time the synchronizing lever 40 is in the process of being reciprocated periodically by the cam 78 (see Figs. 1 to 3), but due to the fact that pawl 39 is rocked as shown the hooked-shaped ends 66 and 67 of the latch 41 and pawl 39 will not become engaged.

When the next bottle 24' is brought up by the conveyer the added pressure causes the star wheel to turn as indicated in Figs. 2 to 4, and to cause one of the ratchet teeth to engage with end 48 of the pawl 39. Further movement of the bottle then causes the pawl to be rocked about its pivot on swinging arm 38 and against the force of spring 52 until it rests against abutment 50 (Fig. 4). When the pawl is in this last position the star wheel is locked against further rotation and the bottle is halted on the conveyer as in Figs. 4 and 5. Assuming, as is indicated in Fig. 4, that the synchronizing lever 40, which is constantly being reciprocated, is so positioned that the engaging surface 79 of the hook-shaped end 66 of latch 41 is beyond the complementary surface 80 of pawl 39, the latch 41 will be rocked slightly away from bolt 63 on its pivot 62. Then as the synchronizing lever moves toward the guide rail 28, the hook-shaped ends 66 and 67 will be forced past each other until the position of Fig. 5 is reached.

When the synchronizing lever again moves away from the rail 28, the surfaces 79 and 80 of the latch 41 and pawl 39 will engage, the synchronizing lever 40 then acting to rotate the swinging arm 38 around its pivot on shaft 55. This disengages the end 48 of the pawl 39 from the teeth on the ratchet wheel, leaving the star wheel 30 free to be turned by the bottle which, because of the conveyer, is constantly pressing on the wheel.

As inspection of Fig. 3 will show, the cam 78 is arranged to provide for a rapid out and in movement of the synchronizing lever 40 with a relatively long period of dwell at the "in" position. Therefore by the time the bottle 24' has moved the wheel 30 through but a small angle of rotation from the position of Fig. 5 the lever 40 will have returned to its "in" position. Thus in Fig. 6 the lever has already started to return to its "in" position and the end 48 of the pawl rests on the periphery of the ratchet wheel just beyond the tooth with which it was engaged in Fig. 5. On continued motion of the lever to its most inward position, the latch and pawl will become disengaged and the pawl will rock to the position of Fig. 2 against abutment 51 under the influence of spring 52. As will be clear, the bottle 24' in passing on into the bottle hooding machine will turn the star wheel once more to the position of Fig. 2 in which position it will remain until the next bottle comes along and the above cycle is repeated.

Where, as is the usual case, a continuous stream of bottles is being fed to the machine, as indicated in Fig. 5, the timing of the synchronizing lever and conveyer is preferably arranged so that by the time each bottle turns the star wheel 30 to rock the pawl to the position of Fig. 5, the synchronizing lever is just starting to swing outwardly. With this arrangement there is an inappreciable halt in the motion of the stream of bottles which makes the feeding action exceedingly smooth.

On the other hand, if the timing device is associated with a machine which handles bottles in groups, for instance two at a time, all that needs be done to properly time a pair of bottles is to change the drive to the synchronizing lever 40 so that it is effective to hold the pawl 39 disengaged from the ratchet wheel long enough for two bottles to pass along the conveyer. Of course in such a case, the end 48 of the pawl would assume the position shown in Fig. 6 when the second bottle of the pair was in the position of bottle 24' of that figure.

Furthermore, if, as is frequently the case, it is desired to run larger or smaller bottles through the machine no adjustment of the star wheel is necessary. All that needs be done is to provide for adjusting the inner side rail 28 laterally as indicated by the bolt 90 and slotted connection 91 for the rail support 92, see Fig. 1.

I claim:

1. In combination with mechanism for operating on containers, a conveyer to feed containers to said mechanism, means for releasing said containers singly, each in timed relation to a cyclic operation of said mechanism for delivery by the conveyer to said mechanism, said means comprising a stop member for said containers as fed by said conveyer and having a stopping position blocking movement of containers by said conveyer and normally movable out of said stopping position by movement of containers along the conveyer, means movable into engagement with the stopping member and tending to normally hold said stop member in its stopping position, a releasing member having a periodic movement in and out of a connectible position with respect to said holding member, and means for connecting said releasing member to said holding member for releasing the latter from engagement with the stop member, the action of said connecting means being determined by the engagement of a container with said stop member.

2. In combination with a mechanism for operating on containers, a conveyer to feed containers to said mechanism, means for releasing said containers singly, each in timed relation to a cyclic operation of said mechanism for delivery by the conveyer to said mechanism, said means comprising a stop member for said containers as fed by said conveyer and having a stopping position blocking movement of containers by said conveyer and normally movable out of said stopping position by movement of containers along the conveyer, means movable into engagement with the stopping member and tending to normally hold said stop member in its stopping position, a releasing member having a periodic movement in and out of a connectible position with respect to said holding member, and means for connecting said releasing member to said holding member for releasing the latter from engagement with the stop member, said connecting means comprising a yieldably mounted latch piece on said releasing member and a yieldably

mounted latch piece on said holding member, said latch pieces being positioned for mutual engagement by engagement of a container with said stop member.

3. In combination with mechanism for operating on containers, a channel for guiding containers to said machine, a conveyer to move containers along said channel, means for timing the delivery of each separate container to the mechanism in relation to the cyclic operation of said mechanism, said means comprising a pivoted stop member mounted adjacent the channel and protruding into said channel for engagement with the containers and for rotation around the pivot by movement of the containers along said channel to release said container, holding means releasably engageable with said stop member to prevent rotation of said member, a releasing member having a periodic movement in and out of a connectible position with respect to said holding member and in timed relation to the operation of said mechanism for disengaging said holding and stop members, and means for connecting said releasing member to said holding member, the action of said connecting means being determined by the engagement of a container with said stop member.

4. In combination with mechanism for operating on containers, a conveyer to feed containers to said machine, timing mechanism associated with said conveyer to release containers singly, each in timed relation to a cyclic operation of said mechanism for delivery by said mechanism, said timing mechanism comprising a first and rotatable container-releasing means operated by movement of the container towards the mechanism, a second means to releasably engage said first named means and stop its rotation, and a third means operated in timed relation to the mechanism to engage the second named means and then move said second means out of engagement with the first named means, said third named means being rendered effective to engage the second named means solely by the engagement of a container with the first named means.

5. In combination with mechanism for operating on containers, a pair of guide rails forming a channel for guiding containers to said mechanism, a conveyer to move containers along said channel and in a horizontal plane, a frame carried on one of said guide rails, a star wheel pivoted on a vertical axis on said frame and located so that as the wheel is rotated its points successively overlie said channel for engagement by successive containers moving along the channel, a ratchet wheel mounted on said axis and in fixed relation to said wheel, a swinging arm pivoted to said frame adjacent said star wheel for swinging movement to and from the pivot for said star wheel, a pawl carried by said swinging arm and arranged to releasably engage the ratchet wheel and hold the star wheel against rotation, a synchronizing lever pivoted to said frame for reciprocation to and from the pawl, means to reciprocate said lever in timed relation to the mechanism, latching means on the lever and latching means on the pawl, normally disengaged, but arranged to engage and rotate the swinging arm about its pivot when the lever is going away from the pawl to thereby disengage the pawl and ratchet wheel, said latches being moved into position for engagement by the engagement of a container with said star wheel when the star wheel is stopped by engagement of the pawl and ratchet.

6. In combination with mechanism for operating on containers, a conveyer for moving containers to said mechanism, a timing device associated with said conveyer to release containers singly each in timed relation to a cyclic operation of said mechanism for delivery to the mechanism, said device comprising a star wheel mounted on a vertical axis adjacent the conveyer with the star wheel projecting over the conveyer in position for the successive points of the wheel to be engaged by successive containers moved towards the mechanism by the conveyer, to thereby rotate the star wheel, an arm pivotally mounted adjacent the star wheel for swinging movement to and from the star wheel, means on the unpivoted end of said arm and means associated with the star wheel for engagement to lock the star wheel against rotation, yieldable means to force the pivoted arm towards the star wheel to engage said two means, a synchronizing lever mounted for swinging movement to positions respectively adjacent to and remote from the means on said arm in periodic relation to the cyclic operation of the mechanism, means on the lever to engage the means on the arm when the lever is moving to its remote position from its position adjacent

the means on the arm to swing the arm away from the star wheel and free the star wheel for rotation, the means on the lever engaging the means on the arm only when a container is in engagement with the star wheel and the star wheel is locked against rotation.

7. In combination with mechanism for operating on containers, a conveyer to feed containers impositively to said mechanism, rotating means for engagement with and rotation by successive containers fed by said conveyer, said means being rotated through a definite arc by the passage of each container, holding means to normally engage the rotating means and limit its rotation, to thereby halt a container, a releasing member having a periodic movement in and out of a connectible position with respect to said holding member and in timed relation to the mechanism, and means for connecting said releasing member to said holding member for releasing the latter from engagement with the rotating member, the action of said connecting means being determined by the engagement of a container with the rotating member when the rotating member is stopped by the holding member.

NORMAN W. LYON.
